JOSEPH HATHAWAY, OF WOODSTOCK, VERMONT.

Letters Patent No. 81,632, dated September 1, 1868.

IMPROVEMENT IN WATER-WHEELS.

The Schedule referred to in these Letters Patent and making part of the same.

TO ALL WHOM IT MAY CONCERN:

Be it known that I, JOSEPH HATHAWAY, of Woodstock, in the county of Windsor, and State of Vermont, have invented a new and useful Improvement in Water-Wheels; and I do hereby declare that the following is a full, clear, and exact description thereof, which will enable others skilled in the art to make and use the same, reference being had to the accompanying drawing, forming part of this specification, in which—

Figure 1 is a vertical central section of my invention, taken in the line $z z$, fig. 3.

Figure 2 is a horizontal section of the shaft of the same, taken in the line $x' x'$, fig. 1.

Figure 3 is a detached sectional plan of the wheel, chutes, and gates.

Figure 4 is a detached side view of a portion of the wheel-shaft.

Similar letters of reference indicate corresponding parts.

This invention relates to a new and improved water-wheel, of that class which is attached to a vertical shaft, and works within a cylindrical case, and has an internal discharge.

The invention consists in a peculiar construction and arrangement of gates and chutes, with means for operating the gates, as hereinafter set forth, whereby the gates may all be moved alike, opened and closed equally, and in case one or more gates should be prevented from closing, on account of any obstruction, the others will not be prevented from closing.

In the accompanying sheet of drawings—

A represents a cylindrical case, into which the water is admitted, said case being placed on any suitable framing or supports, and constructed and arranged in any proper manner.

B represents a hollow cylinder, which is fitted in the lower part of the case A, and extends some distance below it, as shown in fig. 1.

In the upper part of this cylinder there is secured, between flanges $a a$, a series of chutes, C, and gates D, the latter working on rods b in the issues, or between the chutes, and having their outer ends in contact with curved plates e , which are concentric with the rods b , (see fig. 3.)

The outer parts of these gates, beyond the rods b , are longer than their inner parts, so that the gates will, when at liberty, or not held fast, close under the pressure of the water, the closed position being shown in red in fig. 3.

Each gate D has a pin, d , attached at its outer ends, and these pins extend up through curved slots e in the upper flange a , and extend into recesses f , made in the under side of an annular plate, E, which is fitted on the upper flange a , and is moved in the path of a circle by a cam, F, on a vertical shaft, g.

By moving this plate E in one direction, the gates D are all opened simultaneously, on account of the pins d fitting in the recesses f , and they are retained in an open state by the plate. By moving the plate in the opposite direction, the gates are not closed by the plate, but left free to be closed by the pressure of the water, a result due to the longer outer parts of the gates. This will be understood by referring to fig. 3.

By this arrangement, in case one or more of the gates are prevented from closing, the others are not prevented from doing so. This is an important feature, as drift-wood and foreign substances frequently pass into the issues or chutes, and prevent the closing of a gate.

G represents a portion of the wheel-shaft, which is tubular, and fitted on a fixed spindle, H, the latter resting on a bridge-tree, I, in the lower part of the cylinder B, which bridge-tree is raised and lowered by a vertical shaft, J. This part G of the wheel-shaft passes up through a cone, K, within the case A, against the under side of which the top of the wheel abuts. The part G of the wheel-shaft is connected, by a coupling, g^x , with another part, G', said coupling being composed of three bolts b^x , passing through flanges $c^x c^x$, and this part G' is connected with the top part G'' of the shaft by a ratchet-coupling, L, (see fig. 4,) the machinery to be driven being connected to the part G''.

The lower end of the part G of the wheel-shaft runs on a fixed cone, a^x , and the wheel is raised, when desired, by raising the bridge-tree, so that the upper end of the spindle will act against the lower end of G',

and consequently raise G and the wheel; the principal portion of the weight of the wheel being on the top of the spindle H.

By this arrangement, friction is avoided, and the consequent wear and tear.

Besides this advantage, due to the arrangement of the wheel-shaft, there is another and more important one, to wit, the raising of the shaft and millstone, or whatever mechanism is connected with the shaft, independent of the wheel, and running the shaft, when raised on the spindle H, so that the step of the wheel will be relieved of the weight of the shaft and parts connected therewith.

By this ratchet-connection, the machinery connected with the part G'' of the shaft is allowed an independent movement after the wheel is suddenly stopped, or after the water is cut-off from the same, and therefore no part of the machinery or the wheel will be subjected to any sudden strain.

The wheel M is provided with buckets h, the outer ends of which have lips i, (see fig. 3.)

Having thus described my invention, I claim as new, and desire to secure by Letters Patent—

1. The chutes C, in combination with the gates D, pivoted, as shown, and connected to the annular plate E, all arranged to operate in the manner substantially as and for the purpose set forth.

2. The arrangement of the spindle H, resting on the bridge-tree I, in connection with the tubular part G of the wheel-shaft, which turns on H, and rests upon a fixed cone, a^x, and the part G' of the wheel-shaft, which rests on the fixed spindle H, all arranged to operate in the manner substantially as and for the purpose set forth.

JOSEPH HATHAWAY.
